UNITED STATES PATENT OFFICE.

JOHN M. BRIGGS, OF MARTINS FERRY, OHIO.

TRAIN-COALING DEVICE.

1,229,875.

Specification of Letters Patent. Patented June 12, 1917.

Application filed November 14, 1916. Serial No. 131,304.

To all whom it may concern:

Be it known that I, JOHN M. BRIGGS, a citizen of the United States, residing at Martins Ferry, in the county of Belmont 5 and State of Ohio, have invented new and useful Improvements in Train-Coaling Devices, of which the following is a specification.

This invention relates to devices for supplying coal to locomotive tenders of railway trains while in motion.

The invention has for its object to produce a simple and effective device of improved construction, whereby railway trains 15 may be supplied with coal without stopping, the supply being effected gradually, thereby avoiding danger of injury which would be liable to occur if a large or bulky mass of coal were to be suddenly discharged upon 20 the tender of a moving train.

A further object of the invention is to produce a coaling device embodying a movable source of supply partaking of the nature of an electric carrier, the same being 25 adapted to move at a speed commensurate with that of a moving train, and said carrier being equipped with means for gradually feeding the coal to the tender.

With these and other ends in view which 30 will readily appear as the nature of the invention is better understood, the same consists in the improved construction and novel arrangement and combination of parts which will be hereinafter fully described 35 and particularly pointed out in the claims.

In the accompanying drawings has been illustrated a simple and preferred form of the invention, it being, however, understood that no limitation is necessarily made to the 40 precise structural details therein exhibited, but that changes, alterations and modifications within the scope of the claims may be resorted to when desired.

In the drawings,—

45 Figure 1 is a plan view of a device constructed in accordance with the invention.

Fig. 2 is a sectional view taken on the line 2—2 in Fig. 1.

Corresponding parts in both figures of the drawings are denoted by like characters 50 of reference.

15 designates a trestle work having rails 16 on which the carrier 17 moves, said carrier being equipped with rail engaging wheels 18. The carrier supports a motor 19 which 55 drives a feed screw 20, said screw operating in a tubular casing 21 communicating at one end with a source of supply, such as a hopper 22. The tubular casing 21 extends at one end beyond the carrier, said extended 60 end having a discharge spout 23 which is so positioned as to be located directly above a railway track 24 alongside and parallel with which the trestle 15 is erected.

In the operation of this device the carrier 17 is moved at a speed commensurate with that of the train which is to be coaled, the discharge spout 23 having first been brought to a position directly above the tender of the locomotive. The feed screw 70 20 is now rotated, thereby supplying coal from the hopper 22 to the tender.

Having thus described the invention, what is claimed as new, is:—

1. In a device of the class described, a 75 trestle, a carrier movable thereon, said carrier having a hopper, a tubular casing communicating with the hopper and extending beyond one side of the carrier, said casing having a discharge spout, and a driven feed 80 screw in said casing.

2. In a device for supplying coal to moving trains, a railroad track, a trestle erected alongside and in parallel relation to the track, a carrier traveling on the trestle, a 85 source of supply on the carrier, a tubular casing communicating with the source of supply and extending beyond the side of the carrier, said casing having a discharge spout positioned directly above the railroad 90 track, and motor driven means for conveying material through the tubular casing in the direction of the spout.

In testimony whereof I affix my signature.

JOHN M. BRIGGS.

Copies of this patent may be obtained for five cents each, by addressing the "Commissioner of Patents, Washington, D. C."
